UNITED STATES PATENT OFFICE.

JAMES STRATTON AND WILLIAM J. STRATTON, OF BROOKLYN, NEW YORK.

SHADE FOR BURNERS.

SPECIFICATION forming part of Letters Patent No. 397,668, dated February 12, 1889.

Application filed June 21, 1888. Serial No. 277,764. (No model.)

To all whom it may concern:

Be it known that we, JAMES STRATTON and WILLIAM J. STRATTON, both of the city of Brooklyn, in the county of Kings and State of New York, have invented a new and Improved Shade for Burners, of which the following is a full, clear, and exact description.

The invention has for its object to provide a shade for gas or lamp burners, but especially for the latter, of the pivoted or swinging form, and against which the flame will not impinge when the burner is inclined from the vertical position.

To this end the invention consists in the novel construction of shade hereinafter described and claimed.

Reference is to be had to the accompanying drawings, forming a part of this specification, in which similar figures of reference indicate corresponding parts in all the views.

Figure 1 is a side elevation of one of our improved shades, shown in connection with a night-light adapted for use with a gas-burner. Fig. 2 is a plan view thereof; and Fig. 3 is a front elevation, partly in section, of a portion of the bracket and lens.

In the drawings, 10 represents a hollow post or socket adapted to be received on any ordinary gas-burner, 2, to the upper end of which 30 socket is connected, by means of a swing-joint or gas-joint, 11, a lens-frame, 13, the gas-bracket 12 being provided with a burner, 12^a, of the usual form.

Thus far the parts are described and illustrated for the purpose of illustrating the use of the shade, and they may be varied in practice, or the shade may be applied to a lamp-burner.

On the burner 12^a is placed the shade 15, which is formed with an elliptical upper end, 40 15^a, and preferably with a circular bottom, 15^b. In one side of the shade 15, parallel with the major axis of the ellipse, is formed an aperture, 16, and to the said apertured side is secured a funnel-shaped ray-conductor, 17,

through which the light from the burner 12 45 is conducted to the lens, carried by the lens-frame 13.

With this construction, when the burner-bracket, and with it the shade, is turned at an angle to the usual burner, 2, the flame will 50 not impinge against the shade, as would be the case were the shade circular in cross-section throughout.

The shade 15 is preferably provided with a holder consisting of two arms, 18 and 19, of 55 wire, which are carried by the shade, the outer ends of said arms being formed at their free ends—the one with a rigid ring, 18^a, and the other with an aligning-coil, 19^a—above the ring 18^a, and slightly smaller than the said 60 ring.

The ring 18^a is of a less diameter than the lower enlarged part of the gas-burner 12^a, and the coil 19^a is of less diameter than the upper end of the burner. The two serve to steady 65 the shade, and the coil being yielding holds the shade tightly on the burner.

Having thus described our invention, what we claim as new, and desire to secure by Letters Patent, is—

1. The combination, with a shade formed with an elliptical top and provided at one side with a funnel-shaped ray-conductor, of a wire coil or ring carried by the shade and adapted to receive a burner-tip, substantially as described.

2. The combination, with a shade formed with an elliptical top and provided at one side with a funnel-shaped ray-conductor, of the holder consisting of a ring and an aligning-coil, both being supported from and carried by the shade, substantially as described.

JAMES STRATTON.
WILLIAM J. STRATTON.
